**KEYWAY-FORMING MEMBER FOR USE ON
 HIGHWAY FORMS**
 Alfred F. Crone, Williamsville, N.Y., assignor to Acme
 Highway Products Corporation, Buffalo, N.Y.
 Filed Mar. 4, 1963, Ser. No. 262,526
 4 Claims. (Cl. 249—9)

This invention relates to keyway-forming members for use in connection with forming keyways in the longitudinal edges of highway pavement strips.

In the construction of highways comprising two or more longitudinal strips of concrete or other road-forming material, it is customary to form the longitudinal edges of the adjacent strips in such a manner as to form a keyway on one of the strips into which an integral key of the other strip extends, for the purpose of holding the two strips against vertical displacement relatively to each other. The forming of a keyway in one of the strips is accomplished by securing to the paving form for forming the inner edge of the strip a keyway-forming member facing the strip to be poured and consequently, after the concrete has hardened the form may be removed, thus leaving the keyway in the inner edge of the strip facing the adjacent strip to be poured. Consequently concrete of the second strip will pass into the keyway and after hardening will hold the two strips in horizontal alignment. The keyway-forming members are removably applied to the forms so that the forms can again be used for forming highway strips which do not require a keyway.

It is one of the objects of this invention to provide keyway-forming members of improved and durable construction which is capable of withstanding the rough usage to which these forms are subjected, without damage to these members.

It is also an object to provide open-faced keyway-forming members of this type provided with reinforcing members of improved and simplified construction, thus permitting these members to be made of extruded plastic material or of steel members secured together.

A further object is to provide keyway-forming members which are so constructed as to provide clear keyways in the concrete, without permitting concrete to enter the keyway during the pouring of the pavement strip.

In the accompanying drawings:

FIG. 1 is a fragmentary face view of a pair of highway forms arranged in abutting relation to each other and having keyway-forming members embodying this invention applied thereto.

FIG. 2 is a similar view thereof showing the ends of the two paving forms spaced apart.

FIG. 3 is an end elevation of a paving form on an enlarged scale having the keyway-forming member applied thereto, the view being taken when looking in the direction indicated by the arrows on line 3—3, FIG. 2.

FIG. 4 is a sectional elevation thereof on line 4—4, FIG. 2.

FIG. 5 is a longitudinal, central sectional elevation of the keyway-forming member having an alining or coupling member secured to the end portion thereof for cooperation with an adjacent keyway-forming member.

FIG. 6 is a sectional view thereof on line 6—6, FIG. 5.

FIG. 7 is an elevation of two adjoining paving forms having keyway-forming members of modified construction applied thereto.

2

FIG. 8 is a view similar to FIG. 2 showing the two paving forms spaced apart.

FIG. 9 is an end elevation thereof as seen from line 9—9, FIG. 8, on an enlarged scale.

FIG. 10 is a sectional elevation thereof on line 10—10, FIG. 8.

FIG. 11 is a transverse, sectional elevation of the keyway-forming member.

In the construction shown in FIGS. 1—6, 15 represents a highway paving form such as commonly employed in connection with the forming of longitudinal edges of concrete pavements. Concrete is poured against the surface 16 thereof. These paving forms are in common use for forming the longitudinal edges of paving strips and further description of the same is not deemed necessary.

When these paving forms are used in connection with the pouring of concrete or other paving material for a highway of two or more strips in width, the longitudinal edge of a strip to which an edge of an adjoining strip is to be connected, is provided with a part to be interlocked with the adjoining strip to prevent the strips from moving vertically relatively to each other. This interlocking connection is generally in the form of a tongue and groove connection formed in the paving material itself. The groove or keyway is formed by means of a suitable keyway-forming member releasably secured to the form 15 so that this form can also be used at the side of a highway strip in which no keyway is required. This invention relates particularly to the keyway-forming member to be applied to a paving form.

In the construction shown in FIGS. 1—6, the keyway-forming member is preferably made of a plastic material which may be formed by extrusion. This keyway-forming member has an upright wall 20 terminating in upper and lower walls 21 and 22 formed integral with the upright wall and diverging from the same, thus leaving the other face of the keyway-forming member open.

Since these paving forms and the keyway-forming members are subjected to rough treatment while the forms are moved, generally by means of derricks, from one place to another, I consequently prefer to provide the keyway-forming member on the inner face thereof with ribs 24 which extend lengthwise of this member between the upper and lower walls 21 and 22. The ribs 24 extend from the upright wall 20 toward the paving form to a lesser extent than the upper and lower walls 21 and 22, and the advantage of this construction is illustrated in FIG. 6, in which the broken line 25 corresponds to the surface of the upright wall 16 of the paving form. It will be noted that the upper and lower walls 21 and 22 extend into contact with the surface 25 of the paving form, while the ribs 24 are spaced therefrom. The advantage of this construction is that when the keyway-forming member is secured to the upright wall of a form, the edges of the upper and lower walls 21 and 22 will lie in direct contact with the wall 16 of the paving form and thus prevent concrete from passing between the wall 16 of the form and the upper and lower walls 21 and 22 of the keyway-forming member into the interior of this member. Any concrete in the interior of this member would of course interfere with having the keyway receive concrete from the adjacent paving strip to form an interlocking key between the two strips.

In the case of severe pressure or blows applied to the upright wall 20 of the keyway-forming member, this member may be deflected to the extent of having the

the ribs 24 abut against the wall 16 of the paving form and thus prevent further deflection and damage to the keyway-forming member.

The paving forms 15 are provided in their walls 16 at intervals with holes through which bolts may pass for securing the keyway-forming member to the upright wall of the paving form, and in FIG. 4 is shown a keyway-forming member applied to the paving form by means of bolts 28 each having a head 29 and a nut 30, the bolt passing through the keyway-forming member through a hole formed therein midway between the upper and lower edges thereof. The hole in that case would pass between the ribs 24.

When the keyway-forming member is bolted to the paving form the ribs 24 will contact the wall 16 and thus prevent further deformation of the keyway-forming member but at the same time permit forcing the edges of the top and bottom walls 21 and 22 into tight contact with the paving form.

It is generally desirable to provide a connecting or alining member between the adjacent ends of the paving forms such as a connecting member 32 which as shown in FIG. 6, extends between the two ribs 24. This connecting member shown by way of example, is of hollow, rectangular form and may also be of extruded plastic material. One end of the connecting member may be secured to one of the keyway-forming members adjacent to one end thereof in any suitable manner, for example, by means of staples 33, leaving the other ends of the connecting members projecting beyond the end of its keyway-forming member. The other end may then be inserted into the keyway-forming member of an adjacent paving form by passing the connecting member between the ribs 24 of such keyway-forming member. When the two paving forms are connected by means of a connecting member, as shown in FIG. 1, the forms 15 will be in correct alinement with each other and the two keyway-forming members will form a continuous keyway in a pavement strip.

In order to facilitates the securing of the connecting member 32 into the correct position between two ribs 24, these ribs may be provided with inwardly extending flanges 35 so that the connecting member 32 fits snugly and is securely held between the two adjacent keyway-forming members.

It is also possible to make the keyway-forming member of metal, as shown in FIGS. 7-11. In this case the paving forms may be identical with those shown in FIGS. 1-6, being provided with upright webs 16 to which the keyway-forming member may be removably secured so that the paving forms may be used in connection with the edges of the pavement strips which do not require keyways.

The keyway-forming member in this construction is provided with a metal member of the shape required for forming a keyway in the edge of a paving strip, for example, with an upright wall or web 50 formed integral with upper and lower diverging walls 51 and 52. The keyway-forming member is reinforced by means of a member 53 which may be of channel shape having a web 54 suitably secured to the underface of the upright wall 50, for example, by means of welding, and having downwardly extending webs or flanges 55 and 56, the free ends of which however do not extend from the upright wall 50 of the keyway-forming member to the same extent as the upper and lower walls 51 and 52 so that this reinforcing member has the same advantages specified in connection with the construction shown in FIGS. 1-6, namely a tight connection of the ends of the walls 51 and 52 with the upright wall of the form 15 to prevent concrete from entering into the interior of the keyway-forming member.

The keyway-forming member is of course secured to the upright wall of the paving form, for example, either by bolts as shown in FIG. 4 or by means of a bolt or screw 58, FIG. 10, extending through alined holes in the paving

form and the keyway-forming member and having a threaded engagement with a hub of an anchoring member 59. The keyway-forming member shown in FIGS. 1-6 may of course also be secured to the paving form by the construction shown in FIG. 10. The bolt or screw 58 will consequently pull the ends of the upper and lower walls 51 and 52 tightly into engagement with the upright wall 16 of the paving form. The channel-shaped member 53 will reinforce the walls 50, 51 and 52 in the same manner as described in connection with the ribs 24 of FIGS. 1-6 and permit the edges of the upper and lower walls 51 and 52 to contact firmly with the form wall 16.

An alining or connecting member 60 is also used in connection with the keyway-forming members described and may be in the form of a rod or bar of such shape as to fit into the spaces between the walls 55 and 56. This bar is of a width equal approximately to the length of the webs 55 and 56 of the reinforcing member so that it will not hold the edges of the upper and lower walls 51 and 52 out of contact with the paving form. The connecting member 60 may be secured partly within the channel-shaped member of one of the keyway-forming members in any suitable manner, for example, by means of the screw 58, FIG. 8. By making the keyway-forming members of the constructions shown with open faces adjacent to the paving form 15, a better concrete-tight seal is made with the form so that the keyways formed in the paving strips will be free from concrete, thus ensuring a good interlock between adjacent pavement strips.

It will be understood that various changes in the details, materials and arrangements of parts which have been herein described and illustrated in order to explain the nature of the invention may be made by those skilled in the art within the principle and scope of the invention as expressed in the appended claims.

I claim:

1. A keyway-forming member for attachment to a paving form for use in pouring highway strips, said member being slightly elastic and of channel shape including an upright wall having diverging upper and lower walls formed integral therewith and forming an open, interior space between said walls, and a reinforcing rib extending into said space from said upright wall and terminating adjacent to said paving form in position to contact with said form if sufficient pressure is exerted on said upright wall to prevent excessive deformation of said member, said upper and lower walls having their free edges spaced from said upright wall to a greater extent than the free edges of said rib to contact with a paving form to prevent concrete from passing between said form and the edges of said upper and lower walls and into said space.

2. A keyway-forming member according to claim 1 and including an additional reinforcing rib spaced from said first mentioned rib, and a connecting member extending between said ribs at one end of said keyway-forming member and extending outwardly from an end of the same for entrance between the ribs of a keyway-forming member of an adjacent paving form for alining two paving forms.

3. A keyway-forming member according to claim 2 in which said reinforcing ribs terminate at their free ends in

flanges extending toward each other from said free ends for confining said connecting member, said flanges being positioned to engage a paving form to limit the extent to which said upright wall may move toward said paving form.

4. A keyway-forming member for attachment to a paving form for use in pouring highway strips, said member being of slightly elastic material and of channel shape including an upright wall having di-

verging upper and lower walls formed integral therewith and forming an open, interior space between said walls,
and a metal reinforcing member of channel shape secured to said keyway-forming member and having flanges extending into said open space, the edges of said upper and lower walls extending outwardly from said upright wall to a greater extent than the edges of said flanges, for contact with said paving form while the edges of said flanges normally remain out of contact with said paving form. 10
